CLAIM

The ornamental design for a bathtub fill spout, as shown and described.

DESCRIPTION

FIG. 1 is an operational isometric view of a bathtub fill spout mounted flush to a bathtub wall showing my new design; FIG. 2 is an isometric view thereof; FIG. 3 is a front elevational view thereof; FIG. 4 is a rear elevational view thereof; FIG. 5 is a left side elevational view thereof; FIG. 6 is a right elevational view thereof; FIG. 7 is a top plan view thereof; and, FIG. 8 is a bottom plan view thereof showing my design. No claim is made to the shower area or pipe shown in broken lines, they are shown for illustration purposes only.
